CLAIM

The ornamental design for a sporting goods container, as shown and described.

DESCRIPTION

FIG. 1 is a perspective view of the sporting goods container showing a first embodiment of our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a perspective view of the sporting goods container showing a second embodiment of our new design;

FIG. 9 is a top plan view of said second embodiment;

FIG. 10 is a bottom plan view of said second embodiment;

FIG. 11 is a left side elevational view of said second embodiment;

FIG. 12 is a right side elevational view of said second embodiment;

FIG. 13 is a front elevational view of said second embodiment; and,

FIG. 14 is a rear elevational view of said second embodiment.
